US00D569902S

(12) **United States Design Patent** (10) **Patent No.:** **US D569,902 S**
(45) **Date of Patent:** **** May 27, 2008**

(54) **GIFT CARD ENCLOSURE WITH GIFT CARD**

(75) Inventors: **Diana Lo-Min Chang**, Mill Creek, WA (US); **Ji-Hyun K Hwang**, Renton, WA (US)

(73) Assignee: **Amazon Technologies, Inc.**, Reno, NV (US)

(**) Term: **14 Years**

(21) Appl. No.: **29/280,082**

(22) Filed: **May 16, 2007**

(51) **LOC (8) Cl.** **19-01**

(52) **U.S. Cl.** **D19/2**

(58) **Field of Classification Search** D19/1-34; 40/124.01-124.15, 672, 661, 726, 776; 283/72, 283/74, 75, 103, 105, 106; 206/449; 229/92.7, 229/301; D21/385; D20/10, 22, 27, 40, D20/42, 11; D14/435-437; D10/46.1

(57) **CLAIM**

The ornamental design for a gift card enclosure with gift card, as shown and described.

DESCRIPTION

FIG. 1 is a top plan view of the present invention in an unfolded state.

FIG. 2 is a bottom plan view of the present invention in an unfolded state.

FIG. 3 is a perspective view of the present invention in a completely folded and “closed” state; and,

FIG. 4 is a perspective view of the present invention in a partially folded state.

The portions shown in broken line are for illustrative purposes only and form no part of the claimed design.
